INDICATOR MEANS FOR BOWLING PIN
SETTING MACHINES

Morehead Patterson, New York, and Rupert E. Rundell, Rockville Centre, N. Y., assignors to American Machine and Foundry Company, a corporation of New Jersey

Application October 3, 1940, Serial No. 359,518

45 Claims. (Cl. 273—43)

This invention relates to automatic bowling pin setting machines and more particularly to mechanism for indicating the effect of each ball thrown in playing the game. Generally in bowling each player is allotted one or more balls for each frame of the game, in which each frame consists of pins arranged in any desired order on the bed of an alley, such for instance, as ten pins positioned in triangular formation with the apex of the triangle facing the player. After 10 the first ball is thrown, if all the pins are knocked down the result is quite obvious to the player, who knows that he has made what is commonly called a "strike." If, however, less than ten pins are knocked down, it is some advantage to the player to know which pins remain standing and their arrangement on the alley in order that he may determine the best possible way to throw his next ball. If, when he throws the second ball all the pins are knocked down a "spare" 15 results. If, however, one or more pins remain standing, it is still to his advantage to know which pins remain standing in order that he may keep proper score.

It is the main object of my invention, therefore, to provide mechanism which informs the player automatically the effects of the throwing of every ball and advises whether a "strike" or a "spare" has been made, or how many pins remain standing after the throwing of each ball, if neither a "strike" nor "spare" has been made.

According to my invention, I have furnished a pin setter which consists of devices for spotting and respotting pins on a bowling alley having associated therewith means which engage any standing pins after the throwing of the first ball to signal which pins remain standing prior to lifting them from the alley for sweeping, and which also is effective to indicate the presence and position of any standing pins after the throwing of a second ball although if a two-ball per frame game is being played, standing pins are not lifted after the throwing of the second ball.

It is a further object of my invention to provide mechanism which coacts with the pin setting table so that whenever a ball is thrown and the table is lowered after the throwing of the first ball or after the throwing of a second ball, the number and position of pins standing is made apparent to the player by means of a suitable visible signal arranged to correspond with the position of pins on the alley.

It is a further object of our invention to provide mechanism for testing for the presence or

absence of pins standing on a bowling alley bed after the throwing of each ball, and electrically controlled means associated therewith for operating a score board or annunciator to indicate visibly the effect of each ball thrown.

Our invention also consists in the provision of pin handling mechanism carrying setting and resetting devices, together with electrical connections associated with each of said resetting devices for selectively operating an annunciator to indicate visibly the effect of each ball thrown, and to differentiate automatically between "strikes," "spares," and less than ten pins knocked down for each ball thrown.

Our invention further contemplates the provision of novel means in the form of relatively movable switches for completing circuits through our pin resetting devices for operating the machine in a proper manner, and selectively indicating the pin fall per each ball thrown.

It is an added object of our invention to provide an annunciator or score board having thereon visible signals, such as lights, having diameters substantially the same as the maximum diameter of a bowling pin, so that after the throwing of a ball, if pins remain standing, the bowler may be apprised with regards to relative pin size and spacing of the relative positions the remaining standing pins occupy on the alley bed, whereupon he may throw the next ball with more accuracy because of his knowledge of the pin positions, and consequently better his score.

The invention also consists in the provision of a suitable signal board provided with lights designating the position of each pin and so arranged that if all the pins are knocked down on the throwing of the first ball the word "strike" appears to the player and if all the pins are knocked down on the second ball the word "spare" appears.

The invention also contemplates the provision of means for showing which pins are knocked down or remain standing after the throwing of each ball regardless of the fact that neither a "strike" nor a "spare" is made as a result of rolling the ball.

Our invention further consists in mechanism for apprising the bowler of the presence or absence of standing pins on an alley even though pins have been moved off-spot as a result of throwing a ball.

An added object of the invention is to provide a series of pin resetting units which are movable relative to their support, and to pins standing on a bowling alley after a ball has been

thrown, in order to position the units by contact with standing pins for signalling which pins remain standing even though a pin has been moved off-spot on the alley by action of the ball.

With these and other objects not specifically mentioned in view, the invention consists in certain combinations and constructions which will be hereinafter fully described, and then set forth in the claims hereunto appended.

In the accompanying drawings which form a part of this specification, and wherein the several reference characters designate the same or like elements:

Figure 1 is a partial side elevation, partly in section, of a bowling pin setting machine;

Figure 2 is a front elevation of Figure 1;

Figure 3 is a plan view of a suitable pin setter table showing the arrangement of spotters and respotters;

Figure 4 is a sectional elevation on line 4-4 of Figure 3;

Figure 5 is a sectional elevation on line 5-5 of Figure 3;

Figure 6 is a sectional view showing means for admitting suction to the spotter and respotter mechanism;

Figure 7 is a sectional view on line 7-7 of Figure 6;

Figure 8 is a sectional view on line 8-8 of Figure 6;

Figure 9 is a sectional view of a preferred form of respotter showing the valve piston pulled down by suction as would be the case when the pin setter table is lowered and no pins are standing on the alley;

Figure 10 is a sectional view similar to Figure 9 except that in this case a pin standing on the alley has moved the respotter unit into contact with the top plate of the table;

Figure 11 is a sectional view similar to Figures 9 and 10, but showing the respotting mechanism in a neutral position;

Figure 12 is a plan view of the top of Figure 10;

Figure 13 is a sectional view on line 13-13 of Figure 10;

Figure 14 is a schematic plan view showing the wiring leading from the respotters in the pin setter table to the score board (not shown).

Figure 15 is a front view of Figure 14;

Figure 16 is a sectional view on line 16-16 of Figure 14;

Figure 17 is a fragmentary detail view of a part of the structure of Figure 16, drawn to a larger scale;

Figure 18 is a detail plan view of Figure 17; and

Figure 19 is a general wiring diagram showing the various control devices.

Referring to the drawings, in Figures 1 and 2 there is shown a preferred form of our invention associated with an automatic pin setting machine, which may have the same general construction as that shown in co-pending application, Serial No. 339,344 filed June 7, 1940 by Peter M. Nejedly, wherein are provided side frame uprights 1a, 1b, 2a and 2b connected by cross frame members 3 and 4 and longitudinal members 28. Supported on cross frame 4 is a bracket 5 in which one end of a shaft 6 is journalled; the other end is mounted in a bearing in side frame 1b (Figures 1 and 2) and carried by the shaft is a cam 7. Shaft 6 is rotated by means of shaft 49 through sprocket 9 fastened to shaft 49 by means of a sprocket chain 10 tracking sprocket 11 journalled on shaft

12. Through sprocket 13, which is attached to sprocket 11 and also journalled on shaft 12, the drive is transferred by sprocket chain 14 to sprocket 15 mounted upon shaft 6 to rotate cam 7. Bowling pins, which are to be set upon the alley bed, are transferred from a magazine M by means of mechanism which may take the form of that shown in co-pending application, Serial No. 260,901 filed by Rupert E. Rundell on March 10, 1939. A set of pins is placed in predetermined arrangement in the table T, which is raised, lowered and inverted relative to the alley bed. In order to accomplish the desired movement of the table T, a gear segment 16, loosely mounted on shaft 12 and oscillated by means of a cam follower 17 mounted on the segment and engaging cam 7 causes the segment to rotate pinion 18 fixed to shaft 19 supported in arm 20 of bracket 5. Also fixed to shaft 19 is a sprocket 21 about which is trained sprocket chain 22 tracking a sprocket 23 fixed to shaft 24 mounted in brackets 25 supported by the side frames 2a and 2b of the machine.

Mounted on shaft 24 is a pulley 26 about which is trained cable 27 suitably connected at 28 to slide member 31, vertically slideable in guides 8 on side frame member 2a and provided at its lower end with a bracket 38 and a clamp nut 38a which secures shaft 39 of table T in the slide bracket 38 for vertical movement. Also assisting in the vertical movement of the table T is a cable 29 which is trained over pulley 30 supported by shaft 31 journalled in bracket 32 mounted on cross frame 3. Cable 29 extends over a similar pulley 35 mounted on shaft 33 supported by bracket 34 mounted on frame member 4. A counterweight 36 acts to balance the table. While I have only described the mountings of single cables, it will be apparent from Figure 2 that these cables may be provided on both sides of the machine.

As shown in Figures 1 to 5, inclusive, the table T comprises a plurality of pin setter elements S mounted on one side and a plurality of respotting units U mounted on the other side. The arrangement of the setters S and respotting units U conforms to the usual playing positions of pins on the alley bed, but may be varied in any other manner, if desired. The pin handling mechanism and setting devices may be of the same general construction as that shown in the co-pending Nejedly application, above referred to.

According to the referred to Rundell application and the disclosure therein, pins P, which are to be transferred and set upon the bed of a bowling alley, are fed from the pit of the alley by suitable mechanism (not shown), which may include spiral members 40 forming a part of a magazine indicated generally M wherein a plurality of pins, usually ten or more, is arranged in alignment for the removal therefrom of the desired number at a predetermined time by means of grippers 41 which are mounted upon a vertically and horizontally movable conveyor device designated 42 which consists of a plurality of longitudinal bars 43 secured to transverse supports 44. On bars 43 are slidably mounted carriages 45 which in the preferred embodiment are provided with independent gripping fingers 41 which engage and grip the required number of up-ended pins in magazine M for transfer to pin setter S (Figure 1).

The raising and lowering of the table T and operation of the pin transfer mechanism 42 is accomplished by means of a motor 47 mounted

upon frames 1a, 1b of the machine at 48. A stud shaft 49 is driven by means of the sprocket 50 from the motor shaft 51 through a sprocket 52 mounted thereon and a chain 52a. The drive is transferred from shaft 49 to shaft 6 by means of sprocket chain 10 in the manner described in said Nejedly application. In like manner, shaft 53 on which is mounted cam 54, which causes the raising and lowering of pin transfer 42, is driven by means of sprocket 55 mounted on shaft 49 through sprocket chain 56 tracking a sprocket 57 on shaft 53. Cam 54 is provided with a high and a low portion, and whenever the low portion is engaged by cam follower 58 on lever 59, the transfer 42 will be either in pin receiving position over the magazine M or in pin delivering position over setters S. Lever 59 is provided with an arm 60 to which is attached a link 61 connected at 62 to lever 63 provided with an arm 64 pivotally connected to bar 44 forming a cross member of the frame of transfer 42.

The carriages 45 are moved longitudinally along bars 43 by means of pinions (not shown) mounted on shaft 69 journaled in arm 68 which also forms a part of lever 59 mounted on shaft 69. On shaft 69 is provided a sprocket 60 over which tracks a sprocket chain 11 engaging the sprocket 72 on shaft 67 by means of a pinion (not shown) on shaft 69 engaging a suitable driving means, such as a gear segment (not shown) of the type described and disclosed in the above referred to co-pending Nejedly application. In this manner the bowling pins are lifted from spirals 40 by grippers 41, moved clear thereof, transferred longitudinally and located in proper arrangement in pin setters S where they are held while the carriages 45 with the grippers 41 move back to obtain a new set of pins.

After the carriages 45 have delivered the pins from the magazine to the setters S, the pins, gripped firmly therein by suitable means, such as mechanical grippers or holders operated by fluid pressure, such as suction, provided in the table from a suitable source of supply through a conduit 73 and valve D; as shown in the above referred to Nejedly application, are transferred to the alley A. Conduit 74 connects valve D through a flexible conduit 76 to a hollow plug 78 fixed in hollow shaft 39 (Figure 6) so that suction created in conduits 74, 76 can be transmitted through a two-way element 80, which supports one end of a hollow shaft 81 through two-way elements 82 fastened to the other end of member 81 and provided with an opening connecting a hollow plug 84 with a flexible conduit 85. Conduit 85 conducts suction to ducts 87 which are connected to each of the pin setter units S. Since plug 84 is adapted to rotate relative to fixed hollow shaft 39, a circumferential suction passage 83 is formed in element 82, shaft 39 and sleeves 83a which surround shaft 39. In this manner it is possible to create the desired fluid pressure and maintain it regardless of the rotation of table T.

In order to operate the resetting or respotting members U, there is provided a flexible conduit 77 which connects with conduit 75. Flexible conduit 77 connects to a hollow plug member 79 fast in shaft 39, and suction is inducted into the hollow shaft therefrom through a circumferential passage 88 similar to 83 into the bore of plug 89 about which is seated flexible conduit 90 which through ducts 91 supplies the several respotting units U with fluid pressure whenever pins are to be lifted and respotted.

Table or elevator T may consist of a frame F provided with a central barrel or hub 92 mounted upon sleeves 83a for rotation about and relative to stationary shaft 39 in a manner similar to that described and shown in the co-pending Nejedly application above referred to. Since the turning or indexing mechanism forms no specific part of our invention, further description is deemed unnecessary. Barrel 92 is held in proper position upon shaft 39 against lateral movement thereon by means of a collar 93 positioned about shaft 39 and locked in adjusted relationship thereto by means of a set screw 94. Referring to Figures 3, 4, 5 and 6, it will be seen that frame F supports the several setters S in usual substantially triangular pin formation, although any other desired arrangement may be used. Setters S are rigidly mounted upon pipes 87 which are secured to the frame F by means of clamps 95 fastened to frame F.

Pin setters S corresponding to bowling pins, numbers 1, (I), 5, (V), 7, (VII) and 10, (X), in the form shown, are provided with elbows 87a connecting them to the system of pipes 87, while the remaining setters are mounted upon the pipes 87 by means of T units 87b. Attention is called to Figures 4 and 5 which illustrate this method of mounting the setters S. Inasmuch as suction is inducted into the system 87 by means of conduit 85, it will be uniformly distributed through the several pin setters as desired. The table T also comprises an upper plate 96 and a lower plate 98 provided with a number of openings 101 therein corresponding to the number of pin respotting units. These two plates are connected by means of spacers 99 which by means of suitable nuts 99 hold them rigidly separated one from another. Upper plate 96 is secured to frame F by means of brace 100 extending downwardly from the frame F. Slidably mounted upon lower plate 97 and substantially concentric with each of the openings 101 therein, are the bowling pin respotting units U, which are substantially the same as those shown and described in the above referred to application. In order to prevent excessive lateral movement of the respotters U on their support, circular depending flanges 102 are mounted on the under surface of plate 96. Due to the shiftable or "floating" mounting of the respotters U on table T, it is always possible to register the presence of a pin, whether it be on or off-spot. The electrical connections necessary for this purpose are described hereinafter. In order to control the operation of the bowling pin setters, insofar as the application of suction is concerned, when it is desired to lift pins from the alley for respotting, brackets 103 are employed, which support suction conduits 104 to which suction is conducted by means of pipe 81, described previously.

Figures 9 to 13, inclusive, show the detail construction of the resetter units U which have been mentioned hereinabove. The resetter units are each provided with means for conducting suction, automatically registering the presence or absence of standing pins and, therefore, are responsible for the movement of pins to the setters S. Since all of the pin resetter units are the same, only one will be described in detail. In the preferred form, each resetter unit has cooperating therewith a tubular bracket 200 fixedly mounted upon plate 96 in centered relation with reference to an opening 96a therein, and in proper location with respect to the required position of the pins as set and reset upon the alley,

in usual triangular formation or other desired arrangement. A piston 201 is slidably mounted in the bore 201a of the bracket and has associated therewith and fixed thereto a valve 202 provided with a bore 203 having a transverse suction distributing slot 204 in the free end thereof so that suction at all times may be distributed to the pin distributor unit. Suction is conducted from bore 203 through a bore 205 in each resetter unit which communicates with the space above the center of a pin. Coiled about the valve 202 is a spring 206 which bears against the piston and normally tends to urge it upward as shown in Figures 9, 10 and 11. A suction opening 207 is formed in the bore in order to make it possible for suction to be fed from conduit 91 through the bores 203 and 205 for gripping pins. In Figure 10 the suction opening 207 is shown aligned with conduit 91 so that suction is being conducted causing the respotter to grip a pin. Projecting from the upper face of piston 201 is a rod 209 about which is coiled a spring 208 bearing against the upper face of the piston and tending to push it downwardly against the pressure of spring 206. Rod 209 extends upwardly through opening 210 in insulating plug 211 which is secured in the open end of bracket 200. Mounted on rod 209 are insulating plugs 213 and 212 between which is located a conductor disk 214 held thereon by means of a screw 215. Disk 214 is adapted to engage spring contacts 216 mounted 180° apart on insulating plug 211 by means of bolts 218 secured to contacts 217a of wires 217 by means of nuts 219. As shown in Figures 11 and 12, placed substantially 90° apart from contacts 216, are spring contacts 220 which are fixed to insulating plugs 211 by means of bolts 221 and nuts 222 which also secure contacts 222a of line 223. It will be noted that in Figure 10, disk 214 is shown as closing a circuit through spring contacts 216, while in Figure 11 the disk is shown in neutral or "circuit open" position. However, in Figure 9, the disk is shown closing a circuit through contacts 220 and wires 223. A cover 200a may be provided for protection against dust and injury to the switch units.

The make-up of the head of the respotter units U may be similar to that described in the co-pending application, Serial No. 316,468, filed January 31, 1940 by Gottfried J. Schmidt. In this construction the head of a pin left standing, whether it be on or off-spot on the alley, enters the resspotter unit U, causes it to be properly located, is sealed against a gasket G when the table T is lowered, and as the pin pushes the resspotter unit up against the underside of top plate 96 it establishes a complete seal between the head of the pin and the pin setter table so that as the table rises, with suction turned on, the pin is lifted off the alley floor, permitting the fallen pins to be swept off the alley after which the table is lowered and, as the suction is turned off, the pin is released and deposited on the spot from which it was lifted, whereupon the table rises in the manner described in the co-pending Nejedly application above mentioned.

In Figure 9, suction from the line 91 has pulled down piston 201 so that opening 207 is cut off from the source of suction and the pressure of valve 202 bearing against disk 214 is sufficient to hold the unit U against lower plate 97 so that it will not slide between support plates 96 and 97 during the indexing of the table T. From this it follows that as units U are moved down into en-

gagement with the heads of standing pins, as indicated in dot-dash lines in Figure 10, these pins will be sealed to the table and lifted off the alley floor when the table rises.

5 A suitable signal or registering device is provided for informing a bowler of the condition of an alley with respect to pins standing thereon after each ball has been thrown. This device may consist of a board SB (Figure 19), which in 10 the form disclosed may have ten lamps spaced to represent the pins on the alley. If the usual ten pin game is being played, the lamps will be positioned to correspond with the usual triangular formation on the alley. In addition to the lamps, which represent the ten pins and their playing positions, there are also provided automatically illuminated signs bearing the designations strike and spare, one of which will be operated if and when one of the other condition 15 results from the first or second ball thrown.

The several lights are operated on the score or signal board through electric circuits leading from switches in each resspotter unit to its respective lamp on the board SB, as will be set forth in detail hereinafter.

20 Referring to Figures 14 to 18, inclusive, it will be seen that mounted on frame F by means of bolts 225 are brackets 226 to which is fastened, by means of bolts 227, a switch board 234. This 25 board may be made of any suitable insulating material, such as Bakelite or the like, or other material commonly used for this purpose, and is formed in the general shape of a semi-circle with the several switches 228, one being provided for each resspotter, mounted on board 228 by means of bolts and nuts 230 and 231 to which are fastened wires 217 connected in parallel to switches 216 mounted on plugs 218 (Figure 10) of the 30 resspotter units, as described hereinabove.

35 As shown in Figure 17, switches 229 are preferably formed of flat spring material and are mounted for engagement with contacts 232 secured by nuts 233 to plate 234. Thus the current will be transferred through switches 229 from board 234, which rotates with table T, to board 228, mounted on bracket 226 secured to shaft 38, which does not rotate but travels vertically with the table T as it is raised and lowered. The switches 229 and 240 may be arranged in concentric semi-circles and the contacts 232 and 241 likewise arranged in a complementary semi-circular relationship so that whenever plate 234 is rotated relative to plate 228, switches 229 and 240 will make or break circuits through the wires 217 and 223 repeatedly. Wires 217 are connected to contacts 232 by means of nuts 233 and wires 223 are connected to contacts 241 (as shown in Figure 18).

40 As shown in Figures 9, 10 and 12, there are two contacts 216 for each set of wires 217 through which disk 214 makes a circuit, when standing pins push their resspotters U upward as the table T descends (as shown in Figure 10). There are also two contacts 220 for wires 223 which also 45 will be closed by disk 214 (as shown in Figure 9) when no pins are left standing on the alley and the table descends with suction turned on, as described in the referred to Nejedly application. Wires 217 constitute parallel circuits leading from each resspotter unit to its respective lamp on scoreboard SB and the wires 223 comprise a series circuit passing through all the resspotter units and lead to a lamp on the scoreboard which illuminates a sign reading strike when all pins 50 are down. The operation of the two circuits will

be hereinafter fully described in connection with the wiring diagram shown in Figure 19.

As described previously, each resetter unit is also provided with spring switch members 220 which are connected to wires 223 of the strike control circuit. These switches are connected in series through all the pin resetters and two leads thereof are connected by means of nuts 242 in plate 234. Bracket 236 is clamped in such a manner by means of bolt 238a to shaft 39 that a 10 plate 228 extends upwardly therefrom. Plate 234 is so mounted with respect to hub 92 of frame F that switches 229 and 240 engage with the contacts 232 and 241 on plate 234 whenever the pin resetters are located above the alley in position to determine the presence or absence of standing pins thereon. Consequently, when the table T is indexed and lowered towards the alley, 15 circuits will be made through wires 223 and 217 because then switches 229 engage contacts 232 and switches 240 engage contacts 241. It will be seen, therefore, that as the table is moved upwardly and indexed another 180°, the several switches will be opened and the several circuits will be broken.

The leads 217 which are attached to plate 228 extend to plate 243 mounted on bracket 236. Plate 243 is made of non-conducting material having several contacts 244 which are engaged by spring switches 245 secured to plate 246 by means of bolts 247 and nuts 248. Leads 223 are similarly secured to plate 243. Plate 246 is mounted on a bracket 249 fixed to frame 2b. In this manner, despite the fact that carriage 37 mounts the shaft 39 for vertical movement, nevertheless the electric circuits can be made and maintained whenever switch 245 contacts 244 in lowered position of the pin setter table T.

In Figure 19 is shown a wiring diagram suitable for operating the electrical control required for this invention. On the annunciator or score-board SB are shown ten lamps (1 to 10, inclusive) arranged in a triangular formation similar to the order in which the pins are spotted on the alley. There are also two additional lamps, one to illuminate a sign reading strike and the other to illuminate a sign reading spare. Circuit A furnishes current for a starting solenoid, circuit B is a lamp circuit, and circuit C furnishes current for operating the several relays. When the ball B lands in the pit (Figure 1) it closes a switch 251 in a circuit 252, energizing a relay 253 which causes a switch 254 to close circuit 255, thus energizing solenoid 256 which throws a clutch 257 on shaft 49 into engagement with sprocket 52. As the motor 47 has been started before the first ball was delivered, sprocket 52 has been running idly until clutch 257 was thrown into engagement and the drive of the several operating mechanisms will now proceed through shaft 49.

The pin setter table T descends and in case no pins are left standing the respotter units U will remain resting on the bottom plate 97 and as the suction is turned on the piston 201 will be pulled down (as shown in Figure 9) causing switch 220 to close circuit 223. As all the ten respotter units will act similarly, there being no pins left standing, the current C will pass in circuit 223 through closed switch 258, to relay 259, closing switch 260 in circuit 261, energizing relay 262 which closes switch 263 in circuit 264. Circuit 264 passes through lamp 265 which illuminates sign reading strike.

Should the first ball fail to knock down all ten

pins, as the table T descends, any standing pin will enter its respective respotter unit U and as the head of the pin enters the head of the respotter, and the table T settles in its final downward movement, the head of the pin P will lift the respotter away from its position on the bottom plate 97 and up against the underside of the top plate 96 (as shown in Figure 10). When in this position it has automatically admitted the suction element and as gasket 224 seals the top of the respotter against the plate 96 and the head of the pin P is sealed in the head of the respotter, the suction will hold the respotter and the pin in a firm grip while the table T is raised in order to permit the alley to be swept clear of fallen pins. With the respotter and the pin in the position just described, in addition to having admitted suction, it has also caused the switch 216 to close circuit 217 for this particular pin.

Assuming, for example, that only one pin, say number 9, was left standing, the circuits leading to the lamp representing pin number 9 on the score board would operate as follows:

As pin number 9 (Figure 19) closes switch 216 in circuit 217 the circuit C passes through wire 217 and switch 218 to relay 266 which closes switch 267 in circuit 268 which leads to lamp number 9 on the score board SB. This lamp will light up indicating that pin number 9 was left standing on the alley. Similarly any pins left standing on the alley would cause their respective lamps on the score board to be lighted and their grouping on the alley would be visualized on the board.

Should the bowler succeed in knocking down the remaining pin, or pins, with his second ball, the circuits leading to the score board would operate as follows:

As the pin setter table descends and the respotters fail to contact any standing pins, the piston 201 will assume a neutral position (as shown in Figure 11) the suction having been cut off leaving the piston balanced between springs 206 and 208. Both switches 216 and 220 will, therefore, remain open and current C will pass through wire 217 to switch 269, which has been closed by cam 258a as the table T reached its lowermost position. From switch 269 the current passes through wire 270 and switch 271 to relay 272, closing switch 273 in circuit 274. Circuit 274 passes through lamp 275 which illuminates a sign reading spare. Switch 271, which is normally closed, will be opened when any of the lamps, representing a pin standing on the alley, is lighted, as in the case of pin number 9 cited above. The current B passing through wire 268 and through lamp number 9 on the score board to a relay 271, which is energized and opens switch 271, thus breaking the line 270 which controls the current C leading to lamp 275 on the score board. Lamp 275 will, therefore, remain unlighted.

In case the bowler fails to clear the alley with his second ball, the circuits would operate as follows:

When the pin setter table descends, the respotters would contact the pins left standing and as a result the switches 216 corresponding to these pins will be closed and the current would pass through the various circuits, as was described in the case of the number 9 pin left standing and the lamps representing the pins left standing will thus be lighted on the score board. Thus it will be seen that any results obtained by the bowler, either first or second ball,

will be recorded progressively on the score board and in case of pins left standing, their number and grouping will be visualized to the bowlers. As each frame requires two cycles of operation of the machine, one for each ball thrown, a circuit breaker 276 is placed in circuit C to put out the lights on the score board so as to be ready to record the result of the next ball thrown.

In the above description, reference has been made chiefly to annunciating or signalling mechanism for designating which pins remain standing after the throwing of any ball of a frame, because this readily acquaints the bowler with the pins still remaining to be knocked down, and the respective positions occupied by each upon the alley bed. Obviously, this is desirable because it assists the bowler in preparing for throwing his next ball and aids in obtaining a higher score. Particularly is this true if the signal spacing is the same as the actual pin spacing on the alley bed, thereby giving the bowler a plan view of the general arrangement of the pins. When signal lights are used it is proposed that they be made the same in diameter as the maximum diameter of the pins.

However it is within the contemplation of this invention to acquaint a player also as to which pins have been knocked down by each ball thrown and for that reason, if desired, suitable means may be provided for actuating signals, such as lights, corresponding to the positions of the fallen pins. This can be accomplished by any suitable mechanism, as by reversing the circuit connections. For example, all the lights can go on when a strike is made and circuit 223 is closed.

The invention above described may be varied in construction within the scope of the claims, for the particular device, selected to illustrate the invention, is but one of many possible concrete embodiments of the same. It is not, therefore, to be restricted to the precise details of the structure shown and described.

What is claimed is:

1. In a bowling pin setting machine, the combination with an alley bed, of a device for placing pins on said bed in playing arrangement, signalling mechanism, and means carried by said device and positioned to engage the tops of standing pins to operate said mechanism and register to a player the presence or absence of pins on said bed after the throwing of a ball.

2. In a bowling pin setting machine, the combination with an alley bed, of a device for placing non-conducting pins on said bed, means carried by said device and arranged to engage said pins after the throwing of a ball, and signalling mechanism associated with said means for informing the player of the number of pins which remain standing on said bed after each ball thrown.

3. In a pin setting machine, the combination with an alley bed, of means for setting non-conducting pins on said bed, mechanism carried by said means for determining the presence or absence of pins on said bed after the throwing of a ball, and an annunciator for advising the player of the result of each ball thrown.

4. Registering mechanism for use with a bowling pin setting machine comprising a signal device, an alley bed, a support for said device located at a position spaced from said alley bed, a plurality of signals mounted on said signal device, a member movable to and from said bed for determining the number of pins standing on said bed after the throwing of each ball over said bed,

and means connected with said device and member for operating said signals visibly indicating on said device the pins remaining standing.

5. In a bowling pin setting machine for use with a bowling alley having a pin supporting bed, a device for setting and resetting pins in playing arrangement on said bed, and selectively operated mechanism carried by said device setting or resetting pins in response to the number of pins felled by a ball, and separate signalling mechanism associated with said device for signaling to a bowler the result of each ball thrown over said bed.

6. Pin counting mechanism for use with a bowling pin setting machine comprising, a member movable to and from an alley, a signalling device, and means carried by said member and constructed and arranged to differentiate between the presence and absence of pins on said alley after the throwing of a ball for selectively registering on said device to a player the effect of each ball of a frame thrown.

7. In a bowling pin setting machine for use with a bowling alley having a pin supporting bed, mechanism for placing said bowling pins in playing arrangement on said bed comprising, a traveling pin distributing member for setting and resetting pins on said bed, said mechanism including a plurality of pin resetting members operative after the throwing of the first ball to reset pins left standing, electric circuits, an annunciator, a plurality of electric control elements associated with each of said resetter members, and means made operative upon movement of said traveling member and the presence or absence of standing pins after the throwing of a ball for selectively completing one of said circuits and operating said annunciator to record the result of each ball thrown.

8. In a bowling pin setting machine, the combination with an alley bed, of a device for setting and resetting pins on said bed; an annunciator, an electric circuit connecting said resetter device and said annunciator, means for associating said resetting device with said circuit, and means for making said circuit for operating said annunciator to designate the results of each ball thrown over said bed at standing pins.

9. In a bowling pin setting machine for use with a bowling alley having a bed for supporting a plurality of free pins thereon in playing arrangement, signalling mechanism for designating the effect of each ball thrown, including position signals corresponding to bowling pin positions and arrangement on an alley bed, and separate "strike" and "spare" signals, signal operating means mounted for movement to and from said alley, and means operable after a ball has been thrown for moving said signal operating means to and from said alley for selectively operating said mechanism to indicate visibly whether a bowler has made a "strike" or a "spare," or has knocked down less than ten pins by throwing a ball.

10. In a bowling pin setting machine, the combination with an alley bed adapted to support a plurality of bowling pins, and a device for placing pins on said bed, of an annunciator, a plurality of visible signals carried by said annunciator, including separate "strike" and "spare" signals, signal energizing mechanism carried by said device, means for moving said device relative to said bed after the throwing of a ball, and means operative in response to the movement of said

device and the removal of all pins standing on said alley by the first or second ball thrown for selectively operating either said "strike" or said "spare" signal.

11. In a bowling pin setting machine, an alley bed constructed and arranged to support a plurality of bowling pins made of non-conducting material, a setter for placing said pins on said alley bed in playing arrangement, mechanism cooperating with said means for determining the number of pins knocked down per ball thrown, and an annunciator having signal means for registering pin fall, strikes and spares, and devices on said setter coacting with said annunciator for selecting one of said signal means for visibly apprising a bowler of the effect of each ball thrown.

12. In a bowling pin setting machine, the combination with an alley bed, of means for placing bowling pins on said bed in playing arrangement, said mechanism comprising an elevator, pin handling units mounted on said elevator, means for turning said elevator and raising and lowering the same to set and reset pins on said bed, an annunciator, means associated with each of said units for determining the presence or absence of standing pins on said bed after the throwing of a ball, and selectively operated devices made operative by the presence or absence of pins on said alley upon movement of said elevator for operating said annunciator to record the effect of each ball thrown.

13. In a bowling pin setting machine for use with an alley having a pin supporting bed constructed and arranged to support a plurality of free pins in playing arrangement thereon, a device for recording the effect of each ball thrown at said pins, including separate "strike" and "spare" signals, testing mechanism located above said alley, means for moving said mechanism to and from said alley after the throwing of each ball, and means associated with said testing mechanism for selectively operating either said "strike" signal or said "spare" signal dependent upon the knocking over of all pins on said bed by the first or the second ball thrown.

14. In a bowling pin setting machine, an alley bed, and mechanism for placing bowling pins on said bed in playing arrangement, said mechanism comprising an elevator, pin handling devices mounted on said elevator, means for moving said elevator to and from said bed, means associated with each of said devices for determining the presence or absence of standing pins after the throwing of a ball over said bed, a signalling device spaced from said alley, selective means operative according to the number of pins felled by a ball for controlling the operation of said machine, and separate mechanism carried by said elevator dependent upon the movement of said elevator towards said bed for operating said signalling device to inform a player of the number of pins knocked down by each ball thrown.

15. In a bowling pin setting machine for use with a bowling alley having a pin supporting bed, a plurality of non-conducting bowling pins mounted on said bed, a separate pinfall signalling device, and means movable relative to said bed and into engagement with an upper portion of said pins for operating said device to record the number of pins standing or absence of pins on said bed after the throwing of a ball.

16. In a bowling pin setting machine, the combination with an alley bed, of a device having set-

ting and resetting mechanism for setting and resetting pins in playing arrangement on said bed, an electric signaling member associated with each of said resetting mechanisms, an electric circuit for said mechanisms, and selective means operable as a result of each ball thrown and the movement of said device relative to said bed for making said circuit for signaling the result of said thrown ball.

- 10 17. In a bowling pin setting machine for use with a bowling alley having a pin supporting bed, a plurality of non-conducting pins positioned in playing arrangement on said bed, a pin setting device movable to and from said bed including, a plurality of resetting members associated therewith, selectively operative detecting elements associated with each of said members for causing said device to set a new frame of pins if all pins are knocked down by the first ball 20 of a frame thrown, means for moving said device to and from said bed to position said elements in operative relationship with said bed to determine the number of pins knocked down by a ball, a pin-fall signalling device, and means on 25 said setting device operable according to the number of pins felled by each ball and the movement of said device relative to said bed for operating said signalling device and indicating to a player the number of pins standing after each ball thrown.
18. Bowling pin setting mechanism for use with a bowling alley having a pin supporting bed constructed and arranged to support a plurality of non-conducting pins in playing arrangement comprising, a member movable to and from said bed, a pin-fall signalling device, and a plurality of detecting elements carried by said member and operative upon movement of said member towards said alley for operating said signalling device and for signaling to a player the presence or absence of pins on said bed after the throwing of each ball.

19. In a bowling pin setting machine, the combination with an alley bed, of mechanism for setting upon said bed pins left standing thereon after the throwing of the first ball including, resetter devices carried by said mechanism, an electric circuit, control means associated with each of said resetter device connected in said circuit, means for moving said mechanism to engage said resetter devices with standing pins, and separate signaling means operated by said standing pins for closing the circuit through each resetter device engaging said pins to close said circuit and indicate visibly the pins remaining standing.

20. In a bowling pin setting machine, the combination with an alley bed, of mechanism for resetting upon said bed pins left standing thereon after the throwing of the first ball including resetter devices carried by said mechanism, an electric circuit, signal mechanism associated with said resetter devices for visibly designating the number of pins lifted for resetting, and control means also associated with said circuit for selectively operating said signal mechanism to designate the removal of all standing pins from said alley or the number of pins standing as a result of throwing the second ball.

21. In a bowling pin setting machine, the combination with an alley bed, of a traveling pin handling device, a plurality of pin handling units arranged to correspond with the position occupied by the pins standing on said bed carried by said device, an electric circuit connecting each

of said units, means for moving said device into proximity with said bed after the throwing of a ball, signalling means, and means operable upon the removal of all pins of a frame on the first ball thrown and movement of said device towards said bed for closing said circuit and operating said signalling means for visibly designating the results.

22. In a bowling pin setting machine, the combination with an alley bed, of a pin handling conveyor comprising, a plurality of spaced elements mounted on said conveyor, electric control devices, and signalling devices associated with each of said elements, a circuit connecting each of said devices, means for closing said circuit for operating said conveyor to set a new frame of pins if all of the pins standing on said bed are knocked down on the throwing of a single ball, means for preventing completion of said circuit if less than a full frame of standing pins are knocked down by the first ball, and means for operating said signalling devices to apprise a player of the number of pins knocked down by each ball thrown.

23. In a bowling pin setting machine, the combination with an alley bed, of a pin handling conveyor comprising a plurality of pin handling elements mounted in spaced relation on said conveyor, electric control devices, and signalling devices carried by each of said elements, means for moving said conveyor to and from said alley bed to set and reset pins thereon, a normally open electric circuit, means for closing said circuit by movement of said conveyor after the throwing of the first ball of a frame if all of the pins are knocked down thereby, means for maintaining said circuit open by engagement of standing pins with said electric control devices if pins remain standing after the throwing of the first ball, and selectively operated means controlled by said electric control devices for determining the movement of said conveyor, and means for operating said signalling devices on each movement of said conveyor towards said bed for indicating to a player the number of pins knocked down by each ball thrown.

24. In a bowling pin setting machine, mechanism for setting upon a bowling alley pins which have been left standing thereon after the delivery of a bowling ball comprising, a plurality of spaced respotting units, mechanism for setting the full number of pins upon said alley, and selective mechanism automatically operable by the presence or absence of pins on said alley after the throwing of a ball to determine which of said first two mechanisms is to be actuated, said last-named mechanism comprising electrically operated control means mounted on said units, signalling mechanism, and means carried by said first-named mechanism operative after the throwing of a ball constructed and arranged to operate said signalling mechanism, to signal to a player the absence or presence of standing pins.

25. In a bowling pin setting machine, a bowling pin handling mechanism comprising, a shaft, a frame turnably mounted on said shaft, bowling pin setter devices mounted on said frame, bowling pin resetters also mounted on said frame and facing in a different direction from said setters, conduits connecting said setters, and conduits connecting said resetters, selective means for conducting suction through said conduits to said setters and resetters, and electric control means

associated with each of said resetters for controlling the operation of said selective means.

26. In a bowling pin setting machine for use with a bowling alley having a bed constructed and arranged to support a frame of pins in playing arrangement thereon, mechanism for recording the effect of each ball thrown at said pins, said mechanism including separate "strike" and "spare" signals, means movable into the range of standing pins after the throwing of each ball of a frame to test the effect of said ball on said pins, selective means operative upon knocking down of all pins by the first ball for energizing said "strike" signal, and selective means operative in response to the knocking down of all pins by the second ball for energizing said "spare" signal.

27. In a bowling pin setting machine for use with an alley having a bed constructed and arranged to support a plurality of pins in playing arrangement thereon, an annunciator, a set of signals corresponding in number and position to said pins carried by said annunciator, separate sets of "strike" and "spare" signals also carried by said annunciator, a device for placing pins in predetermined positions on said alley, means for moving said device into proximity with said bed after each ball of a frame has been thrown, and means carried by said device and associated with said annunciator for selectively energizing one of said sets of signals.

28. In a bowling pin setting machine for use with a bowling alley having a bed adapted to support a plurality of pins in playing arrangement thereon, a signalling device for registering the effect of each ball thrown at said pins, comprising an annunciator, pin position signals corresponding in number and positions with pins on said bed, and separate "strike" and "spare" signals forming parts of said annunciator, mechanism for placing pins in playing position on said bed, means for moving said mechanism into a position proximate said bed to determine the presence or absence of standing pins, means for energizing selected position signals upon failure of the first ball of a frame to knock down all pins, means for energizing only said "strike" signal if said first ball falls all pins of a frame, and other means for energizing only said "spare" signal if all pins are knocked down by said second ball.

29. In a bowling pin setting machine for use with a bowling alley having a bed adapted to support a plurality of pins thereon in playing arrangement, a signalling device for registering the effect of balls thrown at said pins, comprising pin position signals corresponding in number and position with pins on said bed, and separate "strike" and "spare" signals, means movable relative to said bed after the throwing of a ball to test for the presence or absence of standing pins thereon, selective mechanism associated with said means for energizing selected position signals to register the effect of said ball, means for incapacitating said mechanism if all pins are knocked down by the second ball of a frame, and selective means for operating said "spare" signal to apprise the player of the result obtained.

30. In a bowling pin setting machine for use with a bowling alley having a bed adapted to support a plurality of pins thereon in playing arrangement, signalling mechanism for registering the effect of balls thrown at each set of pins standing thereon, comprising pin position signals, and separate "strike" and "spare" sig-

nals, a frame mounted above said alley, means operative after the throwing of a ball to move said frame into a position adjacent said alley, and selective testing means on said frame for incapacitating said pin position signals and operating said "strike" signal if all pins are knocked down by the first ball thrown.

31. In a bowling pin setting machine for use with a bowling alley having a pin supporting bed, a device for placing pins in playing arrangement on said bed, a travelling support mounting said device for movement to and from said bed, electrical testing mechanism carried by said device for testing for the presence or absence of pins on said bed when said device is adjacent said bed, a fixed support coacting with said travelling support, signalling mechanism, and relatively movable switches associated with said supports for transmitting from said testing means to said signalling mechanism the effect of each ball thrown at pins standing on said bed for visible translation by said mechanism.

32. In a bowling pin setting machine for use with an alley having a pin supporting bed, side supports, a pin handling device mounted for movement in said supports, a plurality of pin handling elements mounted in spaced positions upon said device, electric cables connecting said elements, a stationary switch member mounted on one of said supports, a complementary switch mounted on said device and traveling therewith, and means to raise and lower said device to bring said switches into engagement for completion of circuit through said cables.

33. In a bowling pin setting machine for use with an alley having a pin supporting bed, a pin handling elevator provided with a plurality of pin handling devices movable to and from said bed, means for supporting said elevator for movement, a switch including connections for each of said devices carried by one of said supporting means, a complementary switch carried by said elevator and means for moving said elevator to a position proximate said bed to engage said switches for completion of an electric circuit therethrough.

34. In a bowling pin setting machine, a bowling alley having a pin supporting bed constructed and arranged to support a plurality of pins in playing arrangement thereon, supports located adjacent the sides of said bed, slides mounted for movement on said supports, a shaft mounted in said slides, a pin handling device carried by said shaft, a plurality of pin handling members mounted in placed positions on said device, electrical means connecting each of said members, a stationary circuit closing element mounted on one of said supports, a cooperating circuit making element on said shaft traveling therewith, and means for moving said slides on said supports to a position proximate said bed for bringing said elements into circuit closing position for completing a circuit through said members.

35. In a bowling pin setting machine, a travelling device for placing bowling pins in playing arrangement upon the bed of a bowling alley, means for moving said device into a position adjacent said bed after the throwing of a ball to determine the presence or absence of pins standing thereon, testing elements carried by said device for determining the presence or absence of pins standing on said alley bed after each ball has been thrown, electric connections associated with each of said elements, a testing mechanism switch mounted on said device for travel there-

with, a signalling mechanism, and a complementary stationary switch adapted to be engaged by said first named switch when said device is located at pin testing position for completing said circuits through said connections to actuate said annunciator and record visibly the effects of each ball thrown.

36. In a bowling pin setting device, a travelling device for placing bowling pins in playing arrangement upon the bed of a bowling alley, support members, means mounting said device for movement in said members to and from said bed, testing elements carried by said device for determining the presence or absence of pins standing on said alley bed after throwing each ball, signalling mechanism including separate "strike," and "spare," and pin position signals, electric circuits connecting said signals with said testing elements, stationary circuit making elements mounted on one of said supports, complementary circuit making elements carried by said device and connected in the circuits of each of said testing elements, and means for moving said device into testing position adjacent said alley bed to bring said circuit making elements into engagement for completing circuits between said signalling mechanism and testing elements, thereby to actuate said signalling means and record visibly the effect of each ball thrown.

37. In a bowling pin setting machine for use with an alley having a pin supporting bed constructed and arranged to support a plurality of pins in playing arrangement thereon, signalling mechanism for recording the effect of each ball thrown at said pins, said mechanism including visible position signals corresponding in diameter to the maximum diameter of a bowling pin, and spaced on said mechanism in the same spaced arrangement as the playing arrangement of pins on said alley, said mechanism also including separate "strike" and "spare" signals, testing mechanism located above said bed and cooperating with said signalling mechanism for determining the presence or absence of pins on said alley after the throwing of each ball, means for moving said testing mechanism to and from said bed, and means coacting with said testing mechanism for operating said signalling mechanism to record visibly the effect of each ball thrown.

38. In a bowling pin setting machine, an alley bed constructed and arranged to support a plurality of bowling pins in playing arrangement, a pin setter for placing said pins on said alley bed, signalling mechanism for recording the effect of each ball thrown at said pins including position signals indicating the position each pin occupies upon said bed, means carried by said pin setter for activating selected signals after the first ball is thrown to show the effect of said ball upon said pins, means for incapacitating said selected signals prior to the throwing of the next ball at the remaining standing pins, and means operative after the throwing of next ball for again operating selected pin position signals to indicate visibly the effect of said ball upon said pins.

39. In a bowling pin setting machine, an alley bed constructed and arranged to support a plurality of bowling pins in playing arrangement thereon, a pin setter for placing said pins on said alley bed, signalling mechanism for recording the effect of each ball thrown at said pins including position signals indicating the position each remaining pin occupies upon said bed after a ball has been thrown, and separate "strike"

and "spare" signals, means mounted on said pin setter for activating selected signals after the first ball is thrown to show the effect of said ball upon said pins, selective mechanism for incapacitating said last named means only if all pins are knocked down by the first ball and for activating said "strike" signal, means for incapacitating said pin position signals prior to the throwing of the second ball if all pins are not knocked over by said first ball, and selective means for operating selected pin position signals, or said "spare" signal, if pins remain standing on said bed or are all knocked down, respectively, by said second ball.

40. Pin handling mechanism for a bowling pin setting machine for use with a bowling alley having a bed adapted to support a plurality of pins in playing arrangement thereon, comprising a pin handling device constructed and arranged to turn and move to and from said alley bed, pin setting and resetting units mounted upon said elevator, electric circuits associated with said resetting units, switch means connecting said circuits and mounted on said device for travel therewith, a movable support for said elevator and coacting switch means mounted on said support for engagement by said first named switch means when said device occupies a position adjacent said bed.

41. In a bowling pin setting machine for use with a bowling alley having pin supporting bed, a device for placing pins in playing arrangement on said bed, a fixed support, a traveling support mounting said device for turning, and raising and lowering movement relative to said fixed support between an upper and a lower limit adjacent said bed, and relatively movable switches associated with said supports for operative engagement when said device is at its lower limit.

42. In a bowling pin setting machine, mechanism for resetting upon a bowling alley the pins which have been left standing thereon after the delivery of a bowling ball, mechanism for setting a new frame of pins upon said alley, selective means automatically operable by the presence or absence of pins on said alley after the throwing of a ball for determining which of said mechanisms is to be actuated, signalling means, and means also carried by said first-named mechanism constructed and arranged to be engaged by standing pins for operating said signalling means for visibly signalling to a player the number of pins knocked down by each ball thrown.

43. In a bowling pin setting machine for use with a bowling alley having a bed constructed

and arranged to support a frame of pins in playing arrangement thereon, mechanism for recording the effect of each ball thrown at said pins, said mechanism including, separate "strike" and "spare" signals, means located above said alley and operative after the throwing of each ball of a frame to test the effect of said ball on said pins, selective means operative upon knocking down of all pins by the first ball for energizing said "strike" signal, and selective means in response to the knocking down of all pins by the second ball for energizing said "spare" signal.

44. In a bowling pin setting machine for use with a bowling alley having a bed constructed and arranged to support a frame of pins in playing arrangement thereon, mechanism for recording the effect of each ball thrown at said pins, said mechanism including, separate "strike" and "spare" signals, means located above said alley and operative after the throwing of each ball of a frame to test the effect of said ball on said pins, selective means operative upon knocking down of all pins by the first ball for energizing said "strike" signal, selective means in response to the knocking down of all pins by the second ball for energizing said "spare" signal, and other means operative to indicate the effect when pins remain standing after the throwing of the last ball.

45. In a bowling pin setting machine for use with a bowling alley having a bed adapted to support a plurality of pins in playing arrangement thereon, a signalling device for registering the effect of each ball thrown at said pins comprising an annunciator, pin position signals corresponding in number and positions with pins on said bed, and separate "strike" and "spare" signals forming parts of said annunciator, mechanism for placing pins in playing position on said bed, means operable above said bed for determining the presence or absence of standing pins after the throwing of a ball, means for energizing selected position signals upon failure of the first ball of a frame to knock down all pins, means for energizing only said "strike" signal if said first ball fells all pins of a frame, other selectively operated means for energizing only said "spare" signal if all pins are knocked down by said second ball, and means for energizing selected position signals to indicate the presence or absence of pins standing on said alley as the result of throwing said last ball.

MOREHEAD PATTERSON.
RUPERT E. RUNDELL.
